UNITED STATES PATENT OFFICE.

EDMUND F. KITTOE, OF CHICAGO, ILLINOIS, ASSIGNOR TO THE HOLBROOK & KANE COMPANY, OF SAME PLACE.

VENTILATOR.

SPECIFICATION forming part of Letters Patent No. 395,282, dated December 25, 1888.

Application filed December 31, 1887. Serial No. 259,466. (No model.)

To all whom it may concern:

Be it known that I, EDMUND F. KITTOE, of the city of Chicago and State of Illinois, have invented a new and useful Improvement in 5 Ventilators, of which the following is a specification, reference being had to the accompanying drawings, in which—

Figure 1 is a front elevation, with a portion broken away to show the interior. Fig. 2 is 10 a vertical section on the line 1 1, Fig. 1, and Fig. 3 a horizontal section on the line 2 2, Fig. 1.

My invention is simply an improvement in 15 ventilators, in which a gas-jet, A, is inserted in a flue or chamber, B, closed at the bottom and opening at the top into flue or chimney C. In the construction to which my improvement is applied the "supply-current" enters the chamber C through a contracted orifice, D, directly into and against the gas jet or flame A, creating a blow-pipe action, heating the walls of the chamber B, and thus notably increasing the upward draft into the 20 flue C, and the quantity of air removed from an apartment by the ventilator. In the 25 preferable form of such construction the supply-current of air is, in addition, heated also by causing it to pass through the siphon E, adjacent to the chamber B, before it enters 30 the orifice D.

As the chamber B is closed at the bottom, in order to insure force to the supply-current entering through the orifice D against the gas-flame A, and as the orifice D is somewhat 35 contracted to secure the most effective blast against the gas-flame A, the amount of air carried off through the ventilator is limited to what can pass through a narrow orifice, although by the blow-pipe action of the blast 40 of air against the flame A an amount of heat is developed sufficient to move a much greater quantity of air. This additional air cannot be admitted to the chamber B by making an additional opening at its base, for this would 45 destroy to a greater or less degree the blast through the orifice D against the flame A, and thus materially reduce the heat, which is the motive power in the apparatus. To overcome this difficulty I have devised a simple 50 but what proves to be a very effective device,

which, introduced into the apparatus above described, greatly increases its efficiency and the quantity of air removed through it in a given time. A tube or tubes, F F, are inserted in the chamber B, forming passages open below, at f, to the outer air and above, at f', within the chamber B, preferably at or near the place of its contraction in entering the flue. The passages F may be arranged in a variety of forms; but in the form illustrated 55 in the drawings they are arranged adjacent to the gas-flame A, so that in operation they become heated and a powerful suction is produced therein, carrying large quantities of air up into the flue C, and without producing any 60 diminution in the blast of air entering through the orifice D against the flame A, and producing the heat or motive power. On the contrary, I find that the current of air passing upward through the passages F has an injector-like 65 action upon the air in the chamber B, tending to even increase the blast through the orifice D and the heat thus made available in the movement of a column of air into the flue C. 70

The result, as shown in actual practice, is 75 that the working capacity of the apparatus is greatly increased by the introduction of my improvement, as above set forth.

Having thus described my invention, what I claim as new, and desire to secure by Letters 80 Patent, is—

1. The combination, with a ventilator consisting of a flue or chamber closed at its lower end and opening above into a flue or chimney, and provided with a contracted orifice which 85 directs the incoming air into or against an inclosed gas jet or flame, of one or more flues or passages opening outward to the open air and inward within the chamber above the flame, whereby an increased quantity of air 90 is carried into the upper flue or chimney without impairing the blast of air through the contracted orifice into the flame, substantially as set forth.

2. The combination, with a ventilator con- 95 sisting of a flue or chamber closed at its lower end and opening above into a flue or chimney, and provided with a contracted orifice which directs the incoming air into or against an inclosed gas jet or flame, of one or more flues 100

or passages opening outward to the open air and inward within the chamber above the flame and passing adjacent to the flame without communication therewith, whereby they 5 become heated, accelerating the passage of air through them, substantially as set forth.

3. In a ventilator, the combination of the flue or chamber B, provided with a gas jet or

flame, A, orifice D, and tubes or passages F, adjacent to the flame, and siphon E, substantially as and for the purpose set forth. 10

EDMUND F. KITTOE.
